RAIL STABILIZING DEVICE FOR RAILWAY TRACKS

John G. Mueller, Dayton, Ohio; Emilie P. Mueller, administratrix of said John G. Mueller, deceased

Application June 1, 1931, Serial No. 541,228

12 Claims. (Cl. 238—53)

This invention relates to rail stabilizing devices for railway tracks. It is an object of the invention to provide a rail stabilizing device which will comprise a single unit adapted to engage both the ball and base of a rail; which will be relatively light in weight but sufficiently strong to be highly efficient; very cheap to manufacture and easily installed.

It is a further object of the invention to provide a rail stabilizing device comprising a single unit which will engage the ball, web and base of a rail.

It is a further object of the invention to provide such a device which will be adjustable to rails of different sizes varying from sixty pounds to one hundred thirty-five pounds. To this end the portion of the unit adapted to engage the base of the rail has a convex surface and the opening to receive the tie rod is elongated.

It is a further object of the invention to form the lower outer edge of the rail engaging unit with a concave, convex or inclined surface to adapt the unit to cooperate with various types of washers when the unit is installed on a track.

In the accompanying drawings:

Fig. 1 is a sectional elevation of a railway track with one form of my stabilizing device applied thereto;

Fig. 2 is an enlarged detail sectional view of one rail with such form of my invention applied thereto;

Fig. 3 is a detail view showing one type of washer adapted to be used when the unit is formed with its lower outer end convex;

Fig. 4 is a section taken on the line 4—4 of Fig. 2;

Fig. 5 is an enlarged detail sectional view of another form of my invention showing the position of the unit with respect to the rail when a washer having an opening considerably larger than the tie rod is utilized;

Fig. 6 is a similar view showing the position of the unit with respect to the rail when a washer having an opening snugly fitting the tie rod is utilized;

Fig. 7 is a like view illustrating a modified form of the lower outer end of the unit and a washer in the nature of a wedge; and

Fig. 8 is also a like view illustrating another modified form of the lower outer end of the unit with still another form of washer.

Referring to Fig. 1 of the drawings the opposite rails of the track are indicated by the numerals 1 and 2. A rod 3 extends beneath the rails from a point beyond the outer edge of one rail to a point

beyond the outer edge of the opposite rail and is screw-threaded at each end, as shown at 4, to permit of adjusting the rail stabilizing devices.

In the present instance I utilize a single unit 5 to contact the rail. In Figs. 1 and 2 the unit shown contacts the rail at the ball and the top of the base. The unit 5 is provided with an elongated opening 6 to receive the tie rod 3 and a rib 7 to strengthen it. The unit 5 engages the ball of the rail, as shown at 8, and has a convex surface 9 which engages the upper surface of the base of the rail. This convex surface while contacting different size rails at different points on the upper face of the rail base is held in gripping relation with such surface no matter where the contact may be. A universal washer 10 carried by the tie rod and having an opening larger than the said rod has a convex surface 10a which cooperates with the concave surface 11 of the unit 5 in adjusting the device to different sizes of rails. It will be apparent that the lower outer end of the rail engaging unit may be formed in a variety of ways to coact with various types of washers, and while I have illustrated several forms in the accompanying drawings, I do not wish to be limited to the forms shown, but comprehend within my invention other modifications. A nut 12 is utilized to hold the washer and unit in adjusted position on the rail.

In Fig. 5 I have shown another form of rail stabilizing device comprising a unit 13 contacting a rail 14 at the ball, the web and the upper surface of the base. A rod 15, screw-threaded as shown at 15a carries the unit 13. The unit has a rib 16 to strengthen it and a vertically elongated opening 17 through which the tie rod passes.

The surface of the unit 13 adjacent the upper surface of the rail base is convex, as shown at 18, and is adapted to engage rails of different sizes. The convex surface 18 terminates in a nose 19 which will be forced into gripping relation with the web when the device is in adjusted position with respect to the rail. The upper end of the unit 13 is adapted to contact the ball of the rail, as shown at 20.

Thus it will be seen that with a single unit I am enabled to grip a rail at the ball, the web and the base. A universal washer 21 carried by the tie rod and having an opening larger than the rod, has a convex surface 20a which cooperates with the concave surface 22 of the unit 13 in adjusting the device to different sizes of rails. A nut 23 holds the washer and unit in adjusted position.

In Fig. 6 I have shown a washer 24 having an opening 25 which fits about the rod 15 rather

than around it. The washer 24 has a convex surface 26 which cooperates with the concave surface 27 of the unit 13 in adjusting the device to different sizes of rails.

snugly. With a washer of this type as the nut 23 is tightened the unit 13, when the same is applied to rails of certain sizes, will assume the position shown in Fig. 6.

5 In Fig. 7 I have illustrated the unit having its lower outer end inclined, as shown at 26, to cooperate with a wedge 27 having an opening 28 larger than the tie rod to permit of adjusting the unit to rails of different sizes.

10 In Fig. 8 I have illustrated the unit having its lower outer end convex, as shown at 29, adapted to cooperate with the concave surface 30 of a washer 31 having an opening 32 larger than the rod to permit of adjusting the unit to rails of different sizes.

15 While the constructions herein described constitute preferred embodiments of my invention, it is to be understood that the invention is not limited to the precise forms of construction shown and described and that changes may be made therein without departing from the scope of the invention which is defined in the appended claims.

20 Having thus fully described my invention, what I claim as new and desire to secure by Letters Patent, is:

25 1. In a rail stabilizing device, a single unit having at its lower end an elongated opening, the upper end of the unit adapted to engage the ball 30 of a rail, and an intermediate convex surface to engage the upper surface of the rail base.

30 2. In a rail stabilizing device, a single unit having at its lower end an elongated opening, the upper end of the unit adapted to engage the ball 35 of a rail, an intermediate convex surface to engage the upper surface of the rail base, and a nose to engage the web of the rail.

35 3. In a device of the character described, the combination with a tie rod, of two rail engaging 40 units carried by said rod, one adjacent each side of one rail of a track, said units each self adjusting to effective locking position between lower surface of ball and upper surface of rail base of various makes and sizes of rails, the lower end of each unit having an enlarged opening to receive the tie rod and permit of up and down movement thereon, and means to retain said units in gripping action.

40 4. In a device of the character described, the combination with a tie rod, of two rail engaging 45 units carried by said rod, one adjacent the outer side of each rail of a track, each unit having its upper portion so constructed as to fit any socket of rail heads and prevent its escape therefrom, its central portion convex to engage any degree of upper rail base and its lower portion having an elongated opening to enable up and down movement of said rod extending from rail to rail according to thickness of rail base, stabilizing and 50 unifying rails by wedging upper and central portions between under part of rail head and upper face of rail flange; when nuts on either side of the two rails are screwed up and rod drawn under base of rail.

50 5. In a device of the character described, the combination with a tie rod, of two rail engaging 55 units carried by said rod, one adjacent the outer side of each rail of a track, each unit self adjusting to effective locking position between lower 60 surface of ball and upper surface of rail base of various makes and sizes of rails, the lower end of each unit having an enlarged opening to receive the tie rod and permit up and down movement thereon and means to retain said units in gripping action on the rails.

6. In a device of the character described, the combination with a tie rod, of three rail engaging 65 units carried by said rod, one adjacent the outer side of each rail of a track and one adjacent the inner side of one rail, each unit self adjusting to effective locking position between lower surface of ball and upper surface of rail base of rails of various makes and sizes, the lower end of each unit having an enlarged opening to receive the tie rod and permit up and down movement thereon and means to retain said units in gripping action on the rails.

7. In a rail stabilizing device, a single unit, its upper and lower portion being so constructed to adjust themselves to different rail sections and 15 various sizes of rails, a connecting rod, the lower portion of the unit having an elongated opening to receive said connecting rod on which is mounted ball and socket seating of washer, effectively drawing rod under base of rail as upper and lower 20 portions of unit adjust themselves between lower part of rail head and upper part of rail flange.

8. In a rail stabilizing device, a single unit having its upper portion so constructed as to fit any socket of rail head and prevent its escape 25 therefrom, its central portion convex to engage any degree of upper rail base and its lower portion having an elongated opening to enable up and down movement of connecting rod extending from rail to rail according to thickness of rail 30 base, stabilizing and unifying rails by wedging upper and central portions between under part of the rail head and upper face of rail flange, when nuts on either side of the rail are screwed up and rod drawn under base of rail.

35 9. In a device of the character described, the combination with a tie rod, of four rail engaging 40 units carried by said rod, one adjacent either side of the rails of a track, each unit having its upper portion adapted to engage under side of ball of various types and sizes of rails, and each unit also having its central portion consisting of a cam fitting any degree of upper surface of rail flanges, riding on them toward web of rail until head of upper portion has engaged the ball 45 of the rail, the lower portion of each unit having an elongated opening to receive the tie rod, and means for drawing said rod underneath the bases of the rails and wedging upper and central 50 portions of the units between lower parts of rail heads and upper surfaces of rail flanges to brace and reinforce each individual rail and form a solid unit of the two rails, taking slack out of track and checking weaving motion of rails.

55 10. In a device of the character described, the combination with a tie rod, of four rail engaging 60 units carried by said rod, one adjacent either side of each rail of a track, each unit having its upper portion adapted to engage under side of rail ball, its central portion convex to engage 65 any degree of upper rail base surface and its lower portion having an elongated opening to enable up and down movement of said rod, inclined washers on said rod cooperating with said units, and nuts on said rod adapted to engage 70 said washers, the tightening of the nuts serving to draw the tie rod under bases of rails as upper and lower portions of said units adjust themselves between lower part of rail head and upper part of rail flanges, embracing both sides and bottoms of rails.

75 11. In a device of the character described, the combination with a tie rod, of four rail engaging 80 units carried by said rod, one adjacent either side of each rail of a track, each unit having its 75

upper portion so constructed as to engage under side of rail head, its central portion convex to engage any degree of upper rail base surface and its lower portion having an elongated opening 5 to enable up and down movement of said rod, ball and socket washers cooperating with said units, and nuts on said rod to engage said washers, the tightening of the nuts serving to draw the tie rod under bases of rails as upper and 10 lower portions of said units adjust themselves between lower part of rail heads and upper part of rail flanges, embracing both sides and bottoms of rails.

12. In a device of the character described, the 15 combination with a tie rod, of four rail engaging units carried by said rod, one adjacent either

side of each rail of a track, each unit having its upper portion so constructed as to engage under side of rail head, its central portion convex to engage any degree of upper rail base surface and its lower portion having an elongated opening 5 to enable up and down movement of said rod, concave washers on said rod cooperating with said units, and nuts on said rod adapted to engage said washers, the tightening of the nuts serving to draw the tie rod under bases of rails 10 as upper and lower portions of said units adjust themselves between lower parts of rail heads and upper parts of rail flanges, embracing both sides and bottoms of rails.

JOHN G. MUELLER.
